John B. Pierce Foundation, New York, N. Y., a
corporation of New York

Application November 21, 1932, Serial No. 643,589

3 Claims.

(Cl. 4—3)

My present invention relates to building construction and more particularly to an improved combined bathroom wall unit.

In connection with factory fabricated units 5 adapted to be assembled to form a complete structure, as for example a complete dwelling house, the walls and partitions are built in unit panel construction adapted to be assembled on the job with the minimum of labor and at a 10 minimum of cost, and the erection of the walls and partitions results in defining rooms or chambers of any desired shape and size, depending on the size of the building desired.

One of the necessary rooms in a building, such 15 as a dwelling house, is a kitchen or a bathroom or both, and to obtain the greatest efficiency and simplicity of plumbing, it has been found desirable and feasible to locate the bathroom and kitchen on opposite sides of a single partition wall. The plumbing for the kitchen and bathroom fixtures may be made exceedingly simple in 20 construction, and as it is advantageous to make various fabricated units in as large a size as is possible in view of the convenience in shipping 25 and handling, I have utilized in connection with the building construction, and particularly in connection with the subject matter of my present invention, a so-called factory fabricated rough 30 plumbing unit which forms the subject matter of my co-pending application Serial No. 643,324 filed Nov. 19th, 1932, entitled Factory fabricated rough plumbing unit.

With a factory fabricated rough plumbing unit such as described in the application above 35 referred to, all of the plumbing outlets are concentrated at but a single point and the unit may be arranged as an integral part of the present invention. Under certain circumstances, the wall itself may be dispensed with and the fixtures 40 forming the units of the present invention may be utilized as a partitioning means between the bathroom and the kitchen.

In carrying out my invention, I preferably utilize 45 a single unit composed of a toilet or hopper element and a wash basin element, both assembled side by side into a unitary structure and occupying a portion of one side of the bathroom. Where the partition wall between the bathroom and kitchen is dispensed with, the back of the 50 two units acts as a portion of the wall of the kitchen. It is preferable, however, to utilize at least one panel of a partition as a dividing member between one end of the bathtub in the bathroom and the kitchen.

55 Into the unit thus fabricated, is likewise as-

sembled the factory fabricated waste line unit above referred to, all connected to a vertical riser element, and also incorporated in this unit structure are the usual supply pipes for hot and cold water, both for the toilet and bath, and also the 5 wash basin.

An object of the invention, therefore, is the provision of a wall structure serving as the common wall between a bathroom and a kitchen and incorporating improved features for both bathroom and kitchen uses and so constructed to be installed as a unit, the fixture or fixtures of the bath room being supported at the desired location or locations as a part of the unit.

Another object of the invention embodies suitable means for the installation of plumbing units for bathroom and kitchen uses, respectively, and therewith structurally combined appurtenant parts.

A still further object of my invention resides 20 in the novel feature of utilizing a uni-planar plate member serving as the facing of the unit in which is located and supported a wall hung toilet fixture having the usual or other approved siphon action and the siphon element of which 25 forms part of the waste line. The particular features of the construction of the siphon-like action of the wall hung feature as distinguished from the floor type of toilet does not directly concern my present invention, although it is 30 incorporated therein, but forms the subject matter of a separate and distinct patent application.

In the more preferred embodiment, the wall unit comprises oppositely disposed uni-planar 35 plate members serving respectively as the facing for the kitchen and the bath room, such unit being provided for the mounting of plumbing units for a kitchen, such as a sink, one or more laundry tubs arranged on one side of the wall, and plumbing units such as a wash bowl, toilet, 40 etc., arranged on the other side of the wall structure.

My invention also provides a wall unit comprising spaced oppositely disposed uni-planar plate members serving as wall elements, the space 45 between the wall elements affording a housing for concealing and supporting a flush tank.

My wall unit also provides for the structural combination therewith of vertically arranged shelves and cabinet structure for the bathroom 50 side of the unit, which feature may be utilized singly or combinedly with vertically arranged shelves for a cupboard on the kitchen side of the unit.

Such cabinet structure may also be combined

with suitable spacing, above or below, or both, for housing and concealing suitable illuminating means.

Such cabinet or cupboard features may be employed with or without the flush tank support, and also with or without the plumbing unit, and also with or without the fixture attachment feature, above referred to.

Other objects and novel features of the construction and arrangement of parts comprising the device will appear as the description of the invention progresses.

In the accompanying drawings illustrating a preferred embodiment

15 Fig. 1 is a sectional plan view of bathroom units, taken on the line 1—1 of Fig. 2;

Fig. 2 is a front elevation, partly in section, of the units illustrated in Fig. 1;

20 Fig. 3 is a sectional plan view on the line 3—3 of Fig. 2;

Fig. 4 is a detail section on a relatively enlarged scale and showing the method of attaching unit panels to each other;

25 Fig. 5 is a sectional end elevation on the line 5—5 of Fig. 2;

Fig. 6 is a sectional elevation on the line 6—6 of Fig. 2; and

Fig. 7 is a sectional plan view on the line 7—7 of Fig. 6.

30 Referring to the drawings, and more particularly to Figs. 1 and 2, the unit comprises a uni-planar plate member 11 and a thereto attached frame work, described more fully hereinafter, such uni-planar plate member being arranged to receive at selected locations a wash basin and toilet, and their respective waste piping, referred to more particularly hereinafter, whereby such bath room fixtures are respectively supported by the uni-planar plate member and the frame work 40 of the unit.

45 Figs. 1 and 2 also indicate a wall 10 extending transversely to the unit, also a wall 13 spaced from the wall 10 and also extending transversely to the wall 11; the wall 10 is shown to indicate a closed type of bath room, a door for which is indicated at 14.

The walls 10, 11, 12 and 13 may be made up of a plurality of panel sections of the character set forth and claimed in my copending application 50 Serial #591,395, filed Feb. 6th, 1932, entitled Factory fabricated partition and ceiling construction, now U. S. Patent #1,960,575, granted May 29th, 1934. Preferably, in the construction of a building, usually a dwelling, and for economy in construction, the partition wall 11 lies between the bathroom, above described, and a kitchen. In other words, the partition wall 11 separates the bathroom from the kitchen.

To still further insure economy in construction, 60 I have utilized a factory fabricated waste line unit 15, such as forms the subject matter of my aforesaid co-pending application Serial No. 643-324, such unit being relatively light in weight and factory assembled as a unit, and serves both the usual fixtures in the bathroom as well as the usual fixtures in the kitchen.

70 Preferably, the factory fabricated waste line unit is arranged in the rear portion of the present unit and lies adjacent to and parallel with the partition wall 11 and is directed to be connected to the toilet 16, the wash basin 17, and the bath-tub 18.

The unit is comprised of a framework preferably of metal and substantially rectangular in 75 shape, at the lower righthand front face of which

is attached by welding or in any other suitable manner a plate 20 which extends upwardly from the lower portion of the frame to any suitable height; the frame work includes a dado 19 of general rectangular outline, see Figs. 2, 5 and 6, and cooperating angular bars 19, all suitably connected to one another as a unit to serve for the support of the respective fixtures. On such front plate 20 is hung by means of the bolts 21 and nuts 22 the wall toilet 16, see Figs. 6 and 7. This toilet 16 is connected to the factory fabricated waste line unit 15 by a siphon leg 23. Within the limits of the framework 19 and behind the front wall 20 is arranged the flush tank 24 connected at its lower end to the inlet of the wall toilet 16 by the elbow 25. The operating handle for the flush tank 24 extends outwardly through the front plate 20, as indicated by the numeral 26. Above the flush tank 24 and within the limits of the right hand side of the unit forming the subject matter of the present invention, are arranged a plurality of adjustable shelves 27 and the front of the right hand end is provided with doors 28. Above the shelves 27 and the doors 28 and extending across the full width of the entire 25 unit, see Figs. 5 and 6 is a finished plate 29, also and preferably of metal.

The lower portion of the left hand side of the unit is provided with a removable door 30, provided with a knob 31 and hinges 32, finishing a 30 closure for a compartment 33 beneath the wash basin 17, and in such compartment is housed the trap 34 connected to the wash basin 17 and to the waste line unit 15. The lower portion of the left hand side of the unit and below the compartment 33 is provided with a longitudinal horizontal passage 35, see Figs. 5 and 2, in which is housed the horizontal pipe 36, extending from the bathtub 18 to the outlet 37 of the waste line unit, such pipe also being connected to the vertical riser 38 40 of such waste line unit. Extending upwardly from the horizontal pipe 36 is a pipe containing intermediate its ends a Y-fitting 39, one arm of which is connected to the trap 34 of the wash basin 17 and the other arm of which is closed by a cap 45. 40. When desired, such cap may be removed and connection with such Y-fitting 39 made with apparatus ordinarily found in a kitchen, as for example, a set of tubs, or the ordinary waste line. Extending upwardly from the Y-fitting 39 is a 50 riser 42 connected with a horizontal pipe 43, which in turn is connected to the vertical riser 39. Also in the horizontal pipe 36 and accessible from within the compartment 33, is the usual trap 44. Above the wash basin 17 is arranged a reentrant 55 portion which may carry a mirror 45 and side mirrors 46, the side mirrors 46 being preferably hinged, as indicated at 48, as may also be the mirror 45, which is hinged at 47, see Figs. 3 and 4, to allow access to shelves 49 located within the 60 limits of the unit and behind the elements 45 and 46.

The mirrors or equivalent members 45, 46 extend from a point above the wash basin 17 upwardly to the lower edge of the member 29. The member 29, together with the back 50 of the unit and the top thereof forms a compartment in which is located a source of illumination 51, as an electric lamp and reflector, and the light from such lamp illuminates the mirror 45 and also the mirrors 46, being afforded by the presence of a transparent member 52. It is possible also to illuminate the mirror 45 from the sides by making the members 46 transparent and placing behind 75

the same in a compartment 53 formed in the unit, a source of illumination, as the electric bulb 54, see Fig. 5.

The wash basin 17 and the bathtub 18, are supplied with hot and/or cold water from the hot and cold water supply pipes 55 and 56, respectively, which form an integral part of the unit; the hot or cold or combined hot and cold water is controlled by the operating device 57 mounted on a panel 58 at the side of the unit. The flush tank 24 is supplied with water from the plumbing unit pursuant to regular or other approved practice.

The entire unit as thus described is assembled at the factory and shipped to the place where the same is to be installed, the only operation necessary being the forcing of the upper end of the waste and air-vent pipe 38 through a hole in the ceiling and connecting to the discharging waste line the outlet 37, of the upper floor, see Fig. 2, and correspondingly for any additional floors.

Proper connections of the ends 37, 38 having been made to the waste line of the house, and the hot and cold water pipes 55, 56 being connected to the water supply, the entire installation is complete. This represents a radical saving in the cost of installation as but one hole is cut in the floor and because of the fact that all traps, as the trap 44, are contained within the unit, the unit may be placed in a building in which the floors are merely slabs of concrete or similar material and the use of or necessity for suspended ceilings to accommodate the piping is totally avoided.

Where it is not desired to have a bathtub 18 in the same compartment as the wash basin 17 and the toilet 16, the same may be dispensed with by stopping off an appropriate section of the waste line unit 15, and therefore the compartment or room in which the wash basin 17 and toilet 16 are contained need not be greater in extent than the front face of such units. In such case, it is quite feasible to eliminate the panel partition 11 for its entire length of the bath or wash room, although it may be found preferable to retain one of the panels of the panel partitions and utilize the rear walls of the toilet and wash basin units as the division wall between the bathroom and the kitchen.

The structure embodying my invention, therefore, includes a number of coordinated features of individual novelty. The entire unit is self-contained, including waste line unit, hot and cold water pipes, electric conduits, illuminating fixtures and the like, and all parts other than the toilet and wash basin are contained within the limits of the unit. The unit not only forms a housing for the various parts above enumerated, but also affords closet and illuminating features, as well as a housing for the flush tank for the toilet. In connection with the wash basin, the unit is recessed from the wash basin upward and the recessed portions may be faced with mirrors or left plain as desired, and an illuminating fixture formed integral with and housed within the

unit and above the recessed portions adequately illuminates the mirrors and/or the faces of the recesses.

Further, the unit houses an illuminating fixture or acts as an illuminating fixture to illuminate the bath that may be associated with and at one side of the unit so that when curtains are drawn to screen the bath tub from the remainder of the bathroom fixture, the space above the bath tub is illuminated by the illuminating device contained within the unit through the transparent or translucent partition 60, see Figs. 1 and 2.

The waste line unit housed within the limits of the unit is so located and is of such character as to permit the use of a wall hung toilet while yet retaining the siphon action of the toilet, which is a feature not to be found in any other construction of which I am aware. The unit while adapted for installation in a bathroom or wash room and ordinarily fitting against a wall thereof may be utilized as a substitute for the wall, and in such case, acts itself as the guiding wall or as the major portion of the dividing wall between two rooms as for example between a bathroom and a kitchen in a dwelling house.

Various other features are inherent in my construction and the novelty of such features will be apparent as the description of the invention is studied by those skilled in the art.

I claim:

1. As an improved article of manufacture, a wall structure comprising oppositely disposed uni-planar plate members serving respectively as the front and rear wall structure and affording therebetween an open space, a wash basin fixture located at the front wall structure, a unitary frame secured to and supporting the front and rear wall structure and the wash basin fixture, and supply piping and waste piping for the stated fixture disposed within the spacing between the front and rear wall structure.

2. As an improved article of manufacture, a wall structure comprising oppositely disposed uni-planar plate members serving respectively as the front and rear wall structure and affording therebetween an open space, a toilet fixture located at the front wall structure, a unitary frame secured to and supporting the front and rear wall structure and the toilet fixture, and supply piping and waste piping for the stated fixture disposed within the spacing between the front and rear wall structure.

3. As an improved article of manufacture, a wall structure comprising oppositely disposed uni-planar plate members serving respectively as the front and rear wall structure and affording therebetween an open space, a wash basin fixture and a toilet fixture located at the front wall structure, a unitary frame secured to and supporting the front and rear wall structure and the wash basin fixture and toilet fixture, and supply piping and waste piping for the stated fixture disposed within the spacing between the front and rear wall structure.

ROBERT L. DAVISON.
